BUFFET

Ernest L. Swarts and Orville B. Solie, Rockford, Ill., assignors to The Lane Company, Inc., Altavista, Va., a corporation of Virginia

Filed Nov. 2, 1959, Ser. No. 58,173

Term of patent 14 years

(Cl. D33—6)

Fig. 1.

Fig. 2.

The end not shown is like the end shown, while the back of the buffet is conventionally plain.

We claim:

The ornamental design for a buffet, as shown and described.
